UNITED STATES PATENT OFFICE.

JOHN BURKITT WEBB, OF GLENRIDGE, NEW JERSEY.

DYNAMOMETER.

No. 888,371.

Specification of Letters Patent.

Patented May 19, 1908.

Application filed March 27, 1907. Serial No. 364,921.

To all whom it may concern:

Be it known that I, JOHN BURKITT WEBB, a citizen of the United States, and a resident of Glenridge, in the county of Essex and 5 State of New Jersey, have invented certain new and useful Improvements in Dynamometers, of which the following is a specification.

My invention relates to dynamometers or 10 devices adapted to measure or register power, and particularly to a device adapted to measure or register the power transmitted through a rotating shaft.

For this purpose my invention consists 15 essentially of means to determine the angle of twist or torsion and the corresponding speed of a certain length of said shaft when under stress, and thereby the power transmitted.

20 The nature of my invention will be best understood in connection with the accompanying drawings in which—

Figure 1 is a diagrammatic view illustrating the application of my invention to the 25 determination of the power transmitted by a rotating propeller shaft. Fig. 2 is an enlarged partial vertical section. Fig. 3 is a sectional view on the line 3—3 Fig. 2. Fig. 4 represents an electrically vibrated tuning 30 fork.

Similar characters of reference designate corresponding parts throughout the several views.

In the drawings, 10 is a shaft preferably 35 hollow, which transmits power from, for example, a turbine to a propeller (neither being shown in the drawings). This shaft runs in suitable bearings (not shown) and is usually of several sections bolted together in the 40 usual manner by suitable couplings as the coupling 11 which is made in this instance somewhat heavier and shaped to accommodate the apparatus.

Within the hollow shaft 10 is a second and 45 smaller shaft 12 supported at intervals by suitable bearings and at the inner or turbine end by the ball bearing journal 13. The outer or propeller end is rigidly secured to the hollow shaft 10 as shown, thereby causing 50 the entire shaft 12 to turn with the said shaft 10. To the inner or turbine end of this shaft is fastened a yoke 14 provided with two arms 15 projecting through suitable slots 16 in the coupling 11, so that connection may be made 55 with said shaft from the outside. Two similar armature wheels 17 and 18, preferably

crown wheels, having teeth of suitable shape for their purpose and of a number depending somewhat on the speed of the shaft 10, are mounted on the said shaft 10 as shown. 60 They are preferably made in two halves and with sleeves 19 and 20 of some length, fitting the shaft 10 so that they may be readily put on the shaft and bolted together tight. The wheel 17 is fitted to revolve freely upon the 65 shaft 10, and its position on said shaft is governed by the yoke 14 through the two removable studs 21 which are screwed into the arms 15 of said yoke, and connect the wheel 17 thereto. The wheel 18 is fitted to 70 pinch the shaft 10 at (x) and runs with it.

The sleeves 19 and 20 are provided with 75 lugs 22, 23, so that the two sleeves may be fastened together by bolts. In front of each of the crown wheels are one or more similar, 80 permanent magnets 24 with telephone coils and mounted on the frames 25. These magnets are adjustable endwise in their supports 26, by means of spiral springs, which push the magnets toward the wheels and screws 85 which draw them back, the adjustment being made by turning the milled heads 27. The ends of the properly shaped cores of these magnets project through the respective supports 26 and stand close in front of the teeth 85 of the armature wheels. One or more pole pieces or armature magnets 28 are mounted on the crown wheels 17 and 18 on the reverse side, and face other field magnets 29 mounted on a frame 30. The alternating current 90 generators are not necessarily mounted directly upon the shaft, but may be driven in any suitable way in connection therewith. The magnets 24 are adjustable concentrically with the shaft 10. A portion of the 95 frame 25 is made arc-shaped and graduated as shown, and is concentric with the said shaft and adapted to slide in a similar arc-shaped support of the frame 25. The adjustments of the frames are made through 100 turning the milled heads 31 carrying pinions (not shown) engaging with concealed curved racks (also not shown) of the said frames. By tightening the bolts 32 the arc-shaped pieces may be clamped together and motion 105 of the magnet frames prevented. The magnets 24 are mounted in their respective supports 26, which supports are also notched at the top, as shown, to hold a reading microscope. The two magnets 24 shown in drawings are so mounted on the magnet frames 25 that when one armature tooth arrives or

stands exactly opposite one magnet, another tooth is exactly in front of the other. The magnets on one magnet frame are connected so that they act as one magnet. If only one magnet be mounted on a frame its support must be more accurately set with respect to the center of the shaft 10, whereas two or more magnets tend to correct any error due to an eccentricity of the magnet frame with respect to the shaft center. The two sets of magnets 24 are connected in series and the leads 33 therefrom connected to the telephone receiver 34. The leads 35 and 36 from the two sets of magnets 29 are connected with the recording device 37. This recording device may indicate and record either potential, current or phase.

Fig. 4 illustrates an electrically vibrated tuning fork 38 of variable pitch adjustable by the graduated milled head 39 previously calibrated, and is used in conjunction with the telephone receiver 34 for instantaneously and accurately determining the speed, as hereinafter set forth.

The theory and operation of my dynamometer is as follows:—It is well known that when power is transmitted through a shaft, the said shaft is twisted, and that the degree of this twisting is a function of the power transmitted. If now, a certain length of the shaft has been calibrated; or a calibration determined by calculation, so that the number of degrees twist is known which will be produced by a given moment; it remains only, in order to arrive at a knowledge of the power being transmitted, to provide some accurate means whereby, while the shaft is running, this twist can be measured and the corresponding speed determined.

In order to obtain a considerable length of shaft and yet have the measuring apparatus compact and at an accessible point, the shaft 10 is hollow so that the inner shaft 12 may be inserted as already explained. By this expedient the small inner shaft, fastened to the shaft 10 at or near the propeller end, turns with the said shaft 10 but is not twisted. The yoke arms 15 will therefore move in the slots 16 relatively to the coupling 11. Any twist of the shaft 10 between the point (x) at which the wheel 18 is clamped and the point (y) at which the small shaft 12 is fastened to the hollow shaft will therefore be shown as so many degrees angular displacement or revolution of wheel 17 relatively to wheel 18.

In case the power transmitting shaft is not hollow and therefore no inner shaft can be used, the two wheels 17 and 18 are both adapted to be rigidly attached to the power shaft and at as great a distance apart as possible. To readily determine this angular displacement while running and thereby measure the actual twist of the shaft, I employ the magnets and auxiliary apparatus already described. As the teeth of the crown wheels 17

and 18 revolve in front of the cores of magnets 24, or the pole pieces 28 revolve in front of the magnets 29, alternating currents are induced. These currents are combined in a suitable manner, and the former directed as shown in Fig. 1, to a telephone receiver 34 and the latter to a recording device 37. The currents directed through the telephone receiver 34 if adjusted to be equal in strength and opposite in phase, will neutralize each other and no sound will be heard in the telephone receiver. The teeth of both wheels 17 and 18 then pass their respective electromagnets 24 at the same instant. So soon, however, as the shaft twists, the teeth of one wheel will lag behind those of the other, and the phase is correspondingly altered. A distinct musical tone, whose quality is determined by the number of teeth and other proportions is then emitted by the telephone receiver 34. To determine this displacement, one set of the magnets 24 is now moved concentrically with respect to the shaft 10 by turning the milled head 31 until no sound is heard, thus indicating that the two wheels 90 are again running in the initial relative positions. The amount of movement required to restore this initial condition is then read off on the graduated support 25. This is then a measure of the torque, or by suitable graduation may be read directly as horse power transmitted by the shaft per 1000 revolutions. For the purpose of recording these differences, the stronger currents from magnets 29 are directed through the recording device 37.

To obtain an adjustment for zero I proceed as follows—The propeller is removed or disconnected from the shaft 10 so that the latter may be run at full speed without conveying power. Under these conditions the said shaft remains untwisted and the relative positions of the two wheels 17 and 18 will be the same whether the shaft be running or at rest. With the shaft running thus, the frame on which the measurements are to be made and which I designate "the measuring frame," is set to zero; and the other or "adjusting frame," is set so that the telephone is at zero (emits no sound). The distances of the magnets 24 from their respective wheels are adjusted at the same time, as the currents induced must have the same intensity to bring the telephone to zero. The shaft is then stopped and the "adjusting frame" is permanently clamped to it and the propeller replaced. The test is now proceeded with as previously explained, using the "measuring frame" to determine the twist of the shaft. When the shaft is not twisted, the telephone is at zero when the "measuring frame" reads zero; and if twisted, the reading on the "measuring frame" gives the amount of twist.

Should it be inconvenient to remove the

propeller, the zero reading is found as follows:—By means of the lugs 22 and 23 and bolts, the wheel 17 is fastened to wheel 18; and the studs 21 are unscrewed so as to disconnect the wheel 17 from the shaft 12. The shaft 10 is now run temporarily but does not thereby change the relative positions of the wheels 17 and 18 which are fastened together. The "measuring frame" is then set to zero and the "adjusting frame" set and clamped as before; after which the studs are replaced and the bolts removed from the lugs 22 and 23 so as to make the apparatus ready for a test. Should the shaft 10 not be 10 low, the greatest accessible length ($x z$) is chosen and the wheel 17 fitted to be clamped tight to said shaft at (z).

To make the zero adjustment I proceed precisely as before with wheel 17 bolted to 20 wheel 18, after which the shaft is stopped. I then cement or clamp four short temporary scales on the teeth of the wheels 17 and 18 so that they may be read through a reading microscope laid in the notched tops of the 25 magnet supports 26, and record the four readings. The wheel 17 is then disconnected from wheel 18 and taken from the shaft and clamped at (z). The magnet frame is then adjusted so that the microscopes give the same readings as 30 before,—the wheel 18 being also again inspected to make sure that no change has taken place. The teeth of both wheels will then be in exactly the same positions relative to their magnets as they were before. This 35 adjustment, however, will move the pointer away from the zero mark; and it should then be set back to zero, and the adjusting frame also set back the same amount. The apparatus is then ready for a test.

40 If there be any doubt as to the rigidity of the frame of the ship to which the frames 25 are fastened, a frame of wrought iron tubing can be screwed together connecting the two said frames, and one of these frames then disconnected sufficiently from the ship's frame to make sure that the relative angular position of one of said frames with respect to the other does not change.

The calibration of the shaft may be effected 50 either before or after the installation of the same, or its strength determined by calculation. The shaft having been calibrated or the corresponding calculation made, the torque in foot-pounds corresponding to the 55 scale reading is known, and from it and the speed the horse-power is calculated. The speed may be taken with any suitable speed indicator or recorder operated mechanically by the shaft, or electrically by alternating or 60 other current.

For instantaneous and accurate determination of the speed of the rotating shaft I prefer to employ the electrically vibrated tuning fork shown in Fig. 4. This fork is of variable 65 pitch adjusted by the graduated milled head

previously calibrated, and is used in conjunction with the telephone receiver. Its tone is brought into unison with the telephone tone, and the speed thereby indicated by the reading of the graduated milled head. 70

I claim:

1. In a dynamometer: a rotating and twisting shaft; means in operative relation thereto to generate alternating currents of electricity having a phase difference dependent on the twist of said shaft; and indicating means to indicate this phase difference. 75

2. In a dynamometer: a rotating and twisting shaft; means in operative relation thereto to generate alternating currents of 80 electricity having a phase difference dependent on the twist of said shaft; and indicating and recording means to indicate and record this phase difference.

3. In a dynamometer: a rotating and 85 twisting shaft; two alternating current generators in operative relation thereto to generate alternating currents of electricity having a phase difference dependent on the twist of said shaft; and indicating means to indicate 90 this phase difference.

4. In a dynamometer: a rotating and twisting shaft; two alternating current generators operating in relation to different points of said shaft; means for adjusting, and 95 means for measuring the position of the fields of said generators.

5. In a dynamometer: a rotating and twisting shaft; two alternating current generators operating in relation to different 100 points of said shaft; means for indicating, means for measuring and means for adjusting the position of a field with reference to its armature when the shaft is at rest.

6. In a dynamometer: a rotating and 105 twisting shaft; two alternating current generators operating in relation thereto; adjustable frames carrying the fields of said generators; and means to adjust said frames.

7. In a dynamometer: a rotating and 110 twisting shaft; two alternating current generators operating in relation thereto at different parts of said shaft and having therefore a phase difference dependent on the twist of said shaft; and a telephone receiver 115 in connection with said alternating current generators adapted to indicate the said phase difference.

8. In a dynamometer: a rotating and twisting shaft; two alternating current generators operating in relation thereto at different parts of said shaft and having therefore a phase difference dependent on the twist of said shaft; a telephone receiver in connection with said alternating current generators 120 to indicate the said phase difference; and means adapted in conjunction with said telephone receiver to measure the speed of said rotating shaft.

9. In a dynamometer: a hollow rotating 130

and twisting shaft; an alternating current generator driven from one part of said shaft; a second rotating and non-twisting shaft within said hollow shaft, and connected thereto at another sufficiently remote point; and a second alternating current generator driven by said second shaft.

Signed at New York in the county of New York and State of New York this 21st day of March A. D. 1907.
